ABSTRACT OF THE DISCLOSURE

This disclosure relates to a bridge formed by a plurality of longitudinally adjacent bridging elements, each secured by pivot means to a vertical support with rigid span portions extending between longitudinally adjacent pairs of the bridging elements. The pivot means are the sole articulatable connection between the supports and the bridging elements and are positioned between terminal chamfered ends thereof which cooperate with like chamfered ends of the span portions.

The invention may be applied to road bridges which support a carriageway and may be utilised in the construction of portable overpasses.

According to the present invention as assembly of parts for constructing a bridge includes bridging elements carried by supports which can pivot about a substantially horizontal axis and span portions having ends adapted to co-operate with the ends of the bridging elements so that the bridging elements and span portions can be connected together to provide a bridge length, variations in the vertical height of which can be accommodated by varying the vertical height and angular position of the supports about their pivots.

Thus, the assembly of parts according to the invention can include standard size span portions which can be used with supports of different heights to build up a span of a bridge, the precise vertical curvature of which can be varied according to the requirements of the particular location. Moreover, as the various parts can be standard size, the bridge can be dismantled and re-erected somewhere else using the various parts as required, provided the method of connecting the parts together can be disconnected. The pivoting supports can adapt themselves to different angles by tilting about their pivot points. Preferably chamfered surfaces are provided on the ends of the bridging elements and the ends of the span portions, the upper edges of the chamfers on each end of the bridging elements being displaced inwardly in relation to the lower edges, and spacer pieces may be arranged for fitting between the chamfered surfaces of the bridging elements and the span portions which, if required may be wedge shaped or may have parallel sides.

In order to provide for horizontal curvature of the erected bridge, at least one of the bridging elements and/or span portions may be provided with a longitudinally extending side of greater length than the other and conveniently one of the span portions may thus be curved in a horizontal plane.

In any case, in a preferred arrangement each bridging element and span portion includes a longitudinally extending girder member on which the chamfered ends are formed and in a convenient arrangement each bridging element and span portion includes a pair of transversely spaced girder members.

According to one preferred arrangement the span portions and bridging elements are provided with a number of releasable panels the upper surfaces of which form part of a carriageway operating surface.

Preferably the supports are pivoted to uprights and each

support may be in the form of a bifurcated element, the arms of which are displaced from one another at their outer ends, and between which the associated bridging element extends.

5 With this arrangement each bridging element may be carried by a pair of supports which are displaced from one another along the mutual axis about which they pivot and the ends of the supports may be connected to one another at their upper ends by transversely extending 10 portals or, they may be interconnected by cross-bracing. Safety barriers may be included which can be erected along the sides of the bridge and which comprise a longitudinal extending flexible deflector shield which is arranged at an angle to the vertical and which extends transversely from a lower edge adjacent a carriageway carried by the bridge to an upper edge which is outwardly and upwardly displaced therefrom, and the shield may be made from a mesh material.

The invention also includes a bridge assembled from 20 the parts set forth above.

Thus, a bridge as set forth which can be dismantled and re-erected may have a carriageway surface which is made up from a number of releasable panels, each panel having an upper surface which forms part of the carriageway 25 operating surface.

According to another aspect of the invention a bridge made up from an assembly of parts as set forth above may include a number of bridging elements and span portions, the vertical height of the bridging element supports being 30 arranged so that a carriageway supported by the assembly is of different vertical heights at its ends with relation to a midpoint so that the carriageway constitutes an overpass with respect to another carriageway which passes beneath it.

35 The invention may be performed in various ways but some embodiments will now be described by way of example and with reference to the accompanying drawings in which:

40 FIGURE 1 is a general side elevation of an overpass road bridge according to the invention,

FIGURES 2, 3 and 4 are side elevations of various applications of the bridge,

45 FIGURE 5 is a cross sectional end elevation of a bridge according to the invention,

FIGURE 6 shows three alternative arrangements for supporting the span members.

FIGURES 7a and 7b are cross sectional views showing the use of a concrete or steel portal,

50 FIGURE 8 shows a method of utilising the bridge assembly to extend the width of an existing road on a hillside.

FIGURE 9 is a detail side elevation of various parts according to one construction, in position.

55 FIGURE 10 is a cross sectional end elevation of the parts shown in FIGURE 9,

FIGURE 11 is a plan view showing how the bridging elements can be connected together to form a bridge having a curvature in a horizontal plane,

60 FIGURE 12 is a side view of an alternative construction made in reinforced concrete material, and

FIGURE 13 is a cross sectional view of part of the arrangement shown in FIGURE 12.

FIGURE 1 shows a bridge built according to the invention which is in the form of an overpass to support a carriageway which is intended to pass over a pair of carriageways and which comprises a number of supports 1 the vertical height of which increases to a mid-point at the centre of the bridge. The two roads over which the overpass is intended to pass are indicated by the reference numeral 2. The supports 1 are arranged in transversely spaced pairs and are carried on uprights 3 which stand

on suitable bases indicated at 4. Each of the supports 1 are in the form of a bifurcated element, the arms 5 of which are displaced from one another at their outer ends and the lower ends of the support being pivoted at 6 to a foot 7 which is carried by the upright 3. As the uprights 3 are of different vertical heights the height of the supports is varied. Each pair of supports 1 carries a bridging element 8 which extend transversely between them and the longitudinal length of which is slightly greater than the distance across the bifurcated arms 5 of the supports. Each bridging element 8 comprises a pair of transversely spaced I-section girders 9 which are connected to the outer ends of the bifurcated elements 5 and the ends of which are chamfered so that the upper side of the girder is shorter than the lower side. The upper side of the girder is arranged to support a carriageway in a manner which is to be described in more detail.

A span portion 10 is arranged to extend between each pair of supports, this span portion 10 being of a similar construction to the bridging elements 8 and comprising a pair of lower transversely spaced girders 11 on which a carriageway is supported.

The ends of the girders 11 on the span portions are chamfered in a similar but opposite manner to the ends of the girders 9 the angle being approximately 30° so that when the span portion is lowered into position between the bridging elements the chamfered portions cooperate to initially support it. In the arrangement shown in FIGURE 1 the distance between the supports is a standard size based on a particular unit length so that the distance between any two supports is known. Thus, a standard span portion can be placed in position the length thereof being one or two or three times the standard unit. It will be appreciated that the pivoted mounting of the supports and also the chamfered ends of the span portions and the bridging elements enables the construction to easily stimulate movement due to the expansion and contraction of a metallic construction and assists in the rapid assembly thereof.

At the lower ends of the bridge, where it reaches ground level the bifurcated supports are replaced by smaller supports 12 so that less vertical space is used and the height of the uprights 3 is decreased until the carriage level reaches the road surface 13 from which it is intended to rise.

The same parts can be used to build a number of constructions which can act as an overpass and some alternative arrangements are shown in FIGURES 2, 3 and 4. In each of the cases shown the bridge is used to span a dual carriageway road 2 but it will be appreciated that the assembly can be used for any other purpose for which a bridge is required.

FIGURE 5 is a cross section of an arrangement which can be used with any of the above constructions and which utilises three supports in transverse alignment the pivots being similarly aligned and each support carrying a girder 9 to provide a base for a carriageway indicated at 14.

Any number of supports could be used as is necessary and if required a single support of unitary construction for each bridging element 8 could be utilised.

In the arrangements shown in FIGURE 6 alternative forms of supports are indicated, the length of the bifurcated arms 5a, 5b, 5c and the uprights 3a, 3b being varied, and as will be seen in the right hand portion of the drawing the support or upright is dispensed with, the foot 7c being mounted directly onto a foundation. The arrangement shown at the left hand side of the drawing could be used for a post tensioned precast reinforced concrete construction or structural steel in various lengths. The arrangement shown in the centre could also be made in structural steel or reinforced concrete and the arrangement shown in the right hand side could be made again from structural steel or reinforced concrete or a combination of both in various standard lengths, and various angular bifur-

cations and could be used where the bridge is intended to run at a fairly constant height above the ground.

FIGURE 7a is a cross section through an assembly according to the invention which may be used with any suitable construction and shows the use of portal bracing. The portal 15a can be made from any suitable material such as reinforced concrete, or steel and is arranged to extend transversely between a pair of support arms 5a. In the arrangement shown in FIGURE 7a the uprights 3a are tall and the portal 15a is of short vertical height whereas in the arrangement shown in FIGURE 7b the portal 15b has long sides 16b and the bifurcated supports 5b are of longer vertical height, being pivoted at 6b near ground level. The use of such a portal increasing the head room beneath the supported road way but where such head room is not required scissors bracing could be used as shown for example in FIGURE 5.

In the arrangement shown in FIGURE 8 the assembly is used to extend the width of an existing road. In this case, a support is only provided at one side of the bridging elements and span portions 10 and again the same reference numerals are utilised to indicate the same parts, the reference numeral 2 being used to indicate an existing road and the hill-side being indicated by the reference numeral 17.

FIGURES 9 and 10 show a particular construction according to the invention in more detail and once again the same reference numerals are used to indicate the same parts. As will be seen the construction shown in these figures is made up from fabricated steel and lower ends of the bifurcated arms 5 carry pivot plates 18 through which a pivot pin 19 is passed to pivotally connect each bifurcated arm 5 to its foot 7. The foot 7 is carried on a base plate 20 which is arranged above the column made up of pre-cast concrete blocks 21. The blocks 21 are maintained in position by steel rods 22 which pass through them and which are held down by nuts 23 at their upper ends. The lower ends of the rods 22 are firmly anchored in a base 24 which may be above or below ground level. With this construction it will be appreciated that the height of the uprights 3 can be easily varied by altering the number of blocks, 21.

Diagonal bracing in the form of an angle section girders are indicated by reference numeral 25 extends between each of the transversely spaced arms of a pair of supports 1 to provide the necessary rigidity but these could of course be replaced by a portal 15 as described with reference to FIGURE 7. The upper end of each of the arms 5 is securely welded to a girder 9 which is of I-section and between which extend a pair of transverse cross members 26 which are also in the form of I-section girders. These girders are firmly secured to the girders 9, and stools 27 made from girder cuttings are also indicated and the cross members are cut away so that they extend transversely beyond the width between the girders 9, the extension being indicated at 28 on FIGURE 10. A number of longitudinally extending small I-sections girders 29 are firmly secured to the upper edge of the cross girder 26 and a carriageway 14 is carried on these longitudinal girders.

The construction of the span portions 10 is similar to the bridging portions 8 and comprises the longitudinal transversely spaced girders 10, an appropriate number of transverse girders 30 which perform a similar function to the transverse girders 26, and longitudinally extending smaller I-section girders 31 which are similar to I-section girders 29 on the bridging portions. Stools 32 similar to stools 27 are also provided and the outer ends of the girders 30 are cut away in a similar manner to those of girders 26.

Spacer pieces 33 are provided between the chamfered engagement surfaces 35, 36 on the ends of the girders 9 and 11 so that any difference between them can be accommodated as required. The spacer pieces 33 can therefore be wedge shaped or have parallel sides as shown in

FIGURE 9 and they are held in position by face pieces 34 secured to the bridging element and the span portion. Thus, the load is carried partly between the face pieces 34 and the spacer 33 between the chamfers.

The carriageway 14 which is laid across the bridge is made up from a number of releasable panels 37, each panel extending approximately half way across the carriageway and, in the arrangement shown in FIGURES 9 and 10 being of such a length that each bridging portion carries two such panels. As the various portions of the bridging members and the span portions are of unitary dimension the panels, which are also of a unitary dimension can be accommodated. Each panel comprises a layer of wooden batters 38 which are suitably connected to each other to provide a surface which is covered with asphalt indicated at 39. Each panel 37 is laid in position on the carrier I-section girders 29 and the centre carrier 29 carries a series of up-standing bolts 40. Similar bolts 41 are provided at prepared distances which correspond to the length of the panels along the outer carrier girder 29, so that the outer edges of each panel can be clamped down. The panels can be quickly positioned by placing them between the bolts and when all the panels are in position, retaining clamping members in the form of metal strips 42 are laid over the bolts, suitable holes being provided so that the clamping metal strips can be locked into position by nuts. The longitudinal ends of the panels abut each other and are sealed by tarred sisal seals. The side edges of each panel are stepped, as shown in 43 so that the bolts 41, 42 are below the general surface of the carriageway 14 and a space is provided above the sisal seal, the grooves thus provided between the sides of the panels when in position can be filled with asphalt if desired and rubberised bitumen can be laid in the transverse grooves above the sisal muffs being provided over the nuts. If the bridge is to be dismantled, the asphalt and nut muffs can be removed and the nuts undone so that the complete carriageway can be easily removed.

A wooden curve 44 is provided at the outer edge of the carriageway and is spaced from a series of crash barrier supports 45 by means of a channel section spacer 46. Each of the crash barrier supports is rigidly connected to the outer end of the girder 26 and the upper ends of the supports 45 are interconnected by means of a guard rail 47, an intermediately longitudinally extending guard rail 47a also being provided. A safety barrier in the form of a longitudinally extending flexible deflector shield is also provided this being in the form of a shield of plastic coated galvanised mesh 48 which is arranged at an angle to the vertical and which extends transversely from a lower edge 49 which is connected to the curb 44 and is adjacent the carriageway to an upper edge 50 which is outwardly and upwardly displaced therefrom and which is connected to a point adjacent the other guide rail 47.

The space beneath the channel section spacer 46 and curb 44 can be used to carry electrical services, and in the arrangement shown in FIGURE 10 a drain 51 is also provided for the carriageway 14.

In an alternative arrangement shown in FIGURES 12 and 13 the supports 3 are made from reinforced concrete and the bifurcated arms 5 are cast into the portion which constitutes the longitudinally extending girder 9. In this case the pivot is made from a pair of interengaging curved faces 52, 53 provided at the base of the arms 5 and the upper end of the upright 3. The cross girders 26 are also made from reinforced concrete material and extensions 28 are also provided. In this case the carriageway may be formed as a deck of precast or in situ reinforced concrete. The latter would have some technical advantages, because a deck of this type would be lighter than a precast one. In this arrangement the junctions between the girders 9 and 10 can also be made in situ by the use of a trough shaped removable steel form, indicated in broken lines at 54 which also forms the erection support. In this arrangement changes in horizontal direction of the

carriageway would take place at these points, the shape of the removable steel form being altered appropriately. It will be appreciated that appropriate steel reinforcing will be provided at the joint.

As shown in FIGURE 11 curves in a horizontal direction in the steel arrangement described with reference to FIGURES 9 and 10 would be achieved by forming the girders 10 of only very short length and curving them appropriately. In an alternative arrangement the actual lengths of the girders 10 in a particular length could be arranged so that one was shorter than the other, thus providing the necessary shorting to curve the carriageway in a horizontal plane or the length of the girders 9 on the bridging elements could be arranged in a similar manner.

If required, cross bracing can be arranged between uprights 3, as is shown at 55 in FIGURE 1.

The bridge assembly described above can be used in a number of different ways and if necessary could be used to support a railway, road, or a conveyor or for any other particular requirement.

What I claim is:

1. A bridge comprising a plurality of longitudinally adjacent bridging elements, each of said bridging elements including a rigid generally horizontally extending portion constituting a part of the bridge length, a support beneath each bridging element and between opposite terminal ends thereof, an upright beneath each support, pivot means connecting each support to its upright at a point between the terminal ends of its associated bridging element for pivoting each bridging element about a horizontal axis generally transverse to the bridge length, said pivot means being the sole articulatable connection between said supports and said uprights, rigid span portions extending between longitudinally adjacent pairs of said bridging elements, and means connecting together the rigid span portions and the bridging elements.

2. The bridge as defined in claim 1 wherein several of said pivot points of said supports are disposed at different vertical heights thereby disposing associated bridging elements and the span portions thereof at angles to the horizontal.

3. The bridge as defined in claim 1 wherein said span portions have opposite terminal ends, and the terminal ends of said bridging elements and span portions have cooperative chamfered surfaces.

4. The bridge as defined in claim 1 wherein each support includes a bifurcated element the arms of which are joined to an associated one of said horizontally extending portions.

5. The bridge as defined in claim 1 wherein each support includes a bifurcated element the arms of which are joined to an associated one of said horizontally extending portions, and the arms of said bifurcated elements are joined to said last-mentioned horizontally extending portion inboard of the terminal ends thereof.

6. The bridge as defined in claim 1 wherein said span portions have opposite terminal ends, the terminal ends of said bridging elements and span portions have cooperative chamfered surfaces, and the upper edges of the chamfered surfaces of one of the pair of terminal ends are disposed inwardly in relationship to the lower edges thereof.

7. The bridge as defined in claim 1 wherein said span portions have opposite terminal ends, the terminal ends of said bridging elements and span portions have cooperative chamfered surfaces in opposed relationship, and spacer pieces disposed between the latter-mentioned surfaces of the bridging elements and span portions.

8. The bridge as defined in claim 1 wherein said bridging elements have opposite longitudinal sides, and the length of one of the longitudinal sides of one of the bridging elements is longer than the opposite longitudinal side thereof.

9. The bridge as defined in claim 1 wherein said span portions have opposite longitudinal sides, and the length

of a longitudinal side of one of the span portions is longer than an opposite longitudinal side thereof.

10. The bridge as defined in claim 1 wherein at least one of the span portions is curved in a horizontal plane.

11. The bridge as defined in claim 1 wherein said span portions have opposite terminal ends, the terminal ends of said bridging elements and span portions have cooperative chamfered surfaces, and said chamfered surfaces are defined by terminal end faces of girder members.

12. The bridge as defined in claim 1 wherein said span portions and bridging elements are provided with a plurality of releasable panels having upper surfaces defining the operating surface of a roadway of the bridge.

13. The bridge as defined in claim 1 wherein said span portions and bridging elements are provided with a plurality of releasable panels having upper surfaces defining the operating surface of a roadway of the bridge, and clamping means for releasably securing the panels in position by acting upon edges thereof.

14. The bridge as defined in claim 1 wherein are provided transversely extending portals for securing together transversely adjacent pairs of said bridging elements.

15. The bridge as defined in claim 2 wherein said span portions have opposite terminal ends, and the terminal ends of said bridging elements and span portions have cooperative chamfered surfaces.

16. The bridge as defined in claim 2 wherein each support includes a bifurcated element the arms of which are joined to an associated one of said horizontally extending portions.

5 17. The bridge as defined in claim 2 wherein said span portions have opposite terminal ends, the terminal ends of said bridging elements and span portions have cooperative chamfered surfaces, and the upper edges of the chamfered surfaces of one of the pair of terminal ends are disposed inwardly in relationship to the lower edges thereof.

10 18. The bridge as defined in claim 2 wherein each support includes a bifurcated element the arms of which are joined to an associated one of said horizontally extending portions, and the arms of said bifurcated elements are joined to said last-mentioned horizontally extending portion inboard of the terminal ends thereof.

15 19. The bridge as defined in claim 3 wherein each support includes a bifurcated element the arms of which are joined to an associated one of said horizontally extending portions, and the arms of said bifurcated elements are joined to said last-mentioned horizontally extending portion inboard of the terminal ends thereof.
